CLAIM

The ornamental design for an air conditioner, as shown and described.

DESCRIPTION

1. Air conditioner

Reproduction **1.1** is a front perspective view of the air conditioner;

Reproduction **1.2** is a front view thereof;

Reproduction **1.3** is a back view thereof;

Reproduction **1.4** is a left side view thereof;

Reproduction **1.5** is a right side view thereof;

Reproduction **1.6** is a top plan view thereof;

Reproduction **1.7** is a bottom plan view thereof;

Reproduction **1.8** is a front perspective view of the air conditioner in a condition that the circulator cover is half open;

Reproduction **1.9** is a front view thereof;

Reproduction **1.10** is a back view thereof;

Reproduction **1.11** is a left side view thereof;

Reproduction **1.12** is a right side view thereof;

Reproduction **1.13** is a top plan view thereof;

Reproduction **1.14** is a bottom plan view thereof;

Reproduction **1.15** is a front perspective view of the air conditioner in a condition that the circulator cover is completely open;

Reproduction **1.16** is a front view thereof;

Reproduction **1.17** is a back view thereof;

Reproduction **1.18** is a left side view thereof;

Reproduction **1.19** is a right side view thereof;

Reproduction **1.20** is a top plan view thereof;

Reproduction **1.21** is a bottom plan view thereof;

Reproduction **1.22** is a front perspective view of the air conditioner in a condition that the circulator cover is protruding downward;

Reproduction **1.23** is a front view thereof;

Reproduction **1.24** is a back view thereof;

Reproduction **1.25** is a left side view thereof;

Reproduction **1.26** is a right side view thereof;

Reproduction **1.27** is a top plan view thereof;

Reproduction **1.28** is a bottom plan view thereof;

(Continued)

Reproduction **1.29** is a front perspective view of the air conditioner in a condition that the circulator cover is protruding leftward;

Reproduction **1.30** is a front view thereof;

Reproduction **1.31** is a back view thereof;

Reproduction **1.32** is a left side view thereof;

Reproduction **1.33** is a right side view thereof;

Reproduction **1.34** is a top plan view thereof; and

Reproduction **1.35** is a bottom plan view thereof.

The dash-dash broken lines depict portions of the air conditioner that form no part of the claimed design. The dash-dot broken lines define the boundary of the claimed design and form no part thereof. This is a design for an air conditioner with a round circulator at the upper front part. In the inoperative state, as shown in reproductions **1.1** to **1.7**, the circulator cover is closed. In the operative state, as shown in reproductions **1.8** to **1.35**, the circulator cover is open and then it protrudes.
